US00D592088S

(12) **United States Design Patent**
Miller

(10) **Patent No.:** **US D592,088 S**
(45) **Date of Patent:** **** May 12, 2009**

(54) **LIGHT EMITTING DIODE (LED) WARNING LIGHT**

(75) Inventor: **Roger L. Miller**, Crestwood, KY (US)

(73) Assignee: **Code 3, Inc.**, St. Louis, MO (US)

(**) Term: **14 Years**

(21) Appl. No.: **29/326,155**

(22) Filed: **Oct. 13, 2008**

(51) **LOC (9) Cl.** **10-05**

(52) **U.S. Cl.** **D10/114**

(58) **Field of Classification Search** **D10/109, D10/111, 114; 362/311; D13/180**

See application file for complete search history.

(57) **CLAIM**

The ornamental design for a light emitting diode (LED) warning light, as shown and described.

DESCRIPTION

FIG. 1 is a perspective view of a light emitting diode (LED) warning light showing our new design;

FIG. 2 is a perspective view of the light only of FIG. 1.

FIG. 3 is a front elevation view of the light only of FIG. 1.

FIG. 4 is a right side elevation view of the light only of FIG. 1.

FIG. 5 is a left side elevation view of the light only of FIG. 1.

FIG. 6 is a rear elevation view of the light only of FIG. 1.

FIG. 7 is a top plan view of the light only of FIG. 1; and,

FIG. 8 is a bottom plan view of the light only of FIG. 1.

In the drawings, the broken line showing of a power cord depicts environmental subject matter and forms no part of the claim.
